SAND CONDITIONING APPARATUS

John Herman Seeling, La Crosse, Wis.

Application February 2, 1950, Serial No. 141,964

4 Claims. (Cl. 209—262)

1

This invention relates to sand conditioning apparatus, adapted particularly for use in foundries or similar establishments, but equally serviceable in the conditioning of sand for other purposes.

An object of the invention is to provide an improved sand conditioning apparatus wherein sand can be dropped into a hopper, and wherein said sand drops to a power-driven impeller of the conveyor type, from one end of which the sand is thrown with great force through a screen, thus to effectively screen the sand while providing for the discharge by gravity of the scrap remaining after the operation.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings:

Fig. 1 is a vertical section taken longitudinally through apparatus formed in accordance with the invention.

Fig. 2 is a top plan view.

Fig. 3 is an enlarged section on line 3—3 of Fig. 1.

Fig. 4 is an enlarged section on line 4—4 of Fig. 1.

Referring to the drawings in detail, I provide a wheeled supporting frame including the horizontal longitudinally extending parallel side rails 1 of angle iron or other suitable bar stock, these being rigidly connected at one end by the cross bar 2 of angle iron or other suitable material.

Adjacent their other ends, the side rails 1 support bearings 3 in which are journaled the opposite ends of the axle 4 on the ends of which are mounted the wheels 5.

Rigidly secured to the respective first-named ends of the side rails 1, and extending upwardly therefrom, at a slight angle from the perpendicular, are the inclined supports 6 of suitable bar stock, to the upper ends of which are rigidly connected the upper ends of steeply inclined upper side rails 7 of channel iron material, which, as readily seen from Fig. 1, are inclined at a steep angle, the lower ends of said upper side rails 7 being rigidly connected to the lower side rails 1.

A front cover plate 8 extends across one end of the machine, between the angularly extended supports 6, while one side of the frame can be covered by a side cover plate 9.

From what has been so far described, it will be seen that I provide a rollably mounted supporting frame for my apparatus, the upper side of the frame, defined by the rails 7, being steeply inclined for a purpose to become apparent hereinafter.

Rigidly secured to the undersides of the channel members 7, and extending transversely therebetween, is the inclined scrap slide 10 of plate material, that defines a steeply inclined scrap slide the inlet end of which is at the upper end of said slide, the outlet end of the slide being disposed at the lower end thereof, so that scrap fed through the inlet end of the slide will gravitate swiftly therethrough for discharge at the bottom end of the slide.

The scrap slide 10 is integrally formed at its upper end with an upwardly and backwardly curved wall 11 the upper portions of which is formed with a large opening in which is mounted a screen 12.

Mounted upon the channel members 7 adjacent the upper ends thereof are the bearings 13 in which are journaled a transversely extending roller shaft 14 having mounted thereon for rotation by said shaft, the roller 15, driving the belt 16 on which are provided spaced cleats 17, said belt being disposed parallel to and spaced a suitable distance above the inclined scrap slide 10, with the upper course of the belt being located below the upper end of said wall 11 so that the belt will feed sand to be conditioned into the area of the screen 12.

The bottom end of the endless belt 16 is passed around the idler roller 18 mounted upon the shaft 19 journaled in the bearings 20 that are mounted upon the bottom ends of the channel members 7.

For the purpose of driving the belt, I provide the motor 21 which can be mounted upon a platform extended transversely between and supported upon the lower rails 1, there being secured to the shaft of the motor a small drive pulley 22 around which passes the belt 23 that also passes around the larger driven pulley 24 mounted upon and rotating the shaft 14.

For the purpose of adjustably tightening the belt 16, the bearings 20 are adjustably positioned, and can be repositioned by means of adjusting screws 25 mounted upon the channel members 7 adjacent said bearings 20.

A plurality of upstanding supports 26 is rigidly secured to the respective channel members 7 and extends upwardly from said channel members, these supports 26 being rigidly secured to and supporting a box-like hopper 27 in which is mounted an inclined deflection board 28 which restricts the opening at the bottom of the hopper to a substantially narrow opening positioned immediately above the lower end of the belt 16, as readily seen from Fig. 1.

As seen from Fig. 1, the upper end of the front wall 11 formed upon the scrap slide 10 terminates short of the front wall of the hopper 27, so as to provide a space through which can swing a hinged baffle, there being provided pivot bolts 29 passed through ears 30 formed upon the front wall of the hopper, the pivot bolts pivotally con-

necting to said hopper the baffle 31 provided with the weight 32.

Secured to the respective channel members 7 and extending between the belt rollers is the plate 33 disposed just above the bottom flight of the conveyor belt, this plate being formed at opposite ends with the upstanding end walls 34 and 35 respectively covering the surfaces of the respective rollers. Supporting the entire apparatus in proper position for use is the stand 36 connected to the cross bar 2. This cooperates with the wheels 5 in supporting the apparatus in the position illustrated in Fig. 1.

Considering now the manner of use of the sand conditioning apparatus, it will be noted that the apparatus is readily portable, and can be rolled upon the wheels 5 to any location. After the apparatus has been positioned at the desired location, sand is shoveled or otherwise fed into the hopper 27, while the belt 16 is driven at high speed from the motor 21.

The sand will gravitate through the narrow opening resulting from the provision of the deflection board 28, to the bottom end of the inclined upper flight of the belt 16, and the sand to be conditioned will be carried upwardly upon said belt to the upper end of the apparatus at high speed, after which the sand will be thrown from said upper end of the belt with great force against the screen 12, with the conditioned sand passing through said screen, while the scrap remaining continues to travel along the curved surface of the front wall 11, so that it is fed with considerable velocity through the inlet end of the downwardly inclined scrap slide 6, being discharged at the lower end of said slide.

In this connection, the hinged baffle 31 extends downwardly across the path of the sand to be conditioned, so as to provide a yieldable leveling means for said sand located immediately in advance of the point at which the sand is impelled at high speed from the conveyor. The baffle 31, as will be appreciated, will yield as necessary to the passage of large objects, by reason of its weighted hinged arrangement.

A considerable amount of sand is adapted to be conditioned in this manner, and it will be appreciated that the scrap discharged from the bottom end of the scrap slide can if desired be fed once again through the hopper 27, to condition the sand still further.

What is claimed is:

1. Sand conditioning apparatus including a supporting frame the upper surface of which is inclined, a scrap slide mounted upon said inclined upper surface and including an upwardly and backwardly curved front wall, a screen in said front wall of the scrap slide, an impeller belt mounted above the scrap slide and positioned to discharge material through said screen, a hopper mounted upon the frame above said belt, for feeding material to the belt, and means for driving the belt at high speed, thus to cause material to be conditioned to be carried upwardly by said belt and discharged with velocity against said screen, whereby conditioned sand will pass through the screen and scrap will gravitate for discharge through the inclined scrap slide, said screen being disposed wholly out of the path of said gravitating scrap material, whereby to limit passage through the screen to material discharged upwardly thereagainst.

2. Sand conditioning apparatus including an inclined supporting frame, an inclined scrap slide mounted thereon, a screen mounted at the upper

end of said scrap slide, an endless cleated conveyor belt mounted upon the frame above said slide and inclined correspondingly to the slide, a hopper positioned to discharge material into the bottom end of the conveyor to be carried upwardly by the conveyor toward the screen, and means for driving the conveyor at high speed, thus to cause the material carried upwardly thereby to be impelled with substantial velocity against the screen, said screen being located to provide a deflection means for scrap denied passage through the screen, deflecting said scrap to the upper end of the inclined scrap slide, said screen being disposed wholly out of the path of said gravitating scrap material, whereby to limit passage through the screen to material discharged upwardly thereagainst.

3. Sand conditioning apparatus comprising a wheeled supporting frame having a pair of spaced parallel steeply inclined upper side rails, a conveyor slide extending between and secured to said side rails, said slide comprising a solid plate covering the entire space between the side rails, an arcuate deflection wall integral with the upper end of said plate and inclined upwardly and backwardly from said upper end of the plate, said deflection wall having an opening of substantial size, a screen covering said opening and curved correspondingly to said wall, said screen comprising the upper portion of said deflection wall, the lower portion of said wall being imperforate and being formed as a curved extension of the screen, spaced conveyor rollers extending transversely between the rails and mounted upon said rails and positioned above said scrap slide, an endless cleated conveyor belt extending around said rollers and inclined correspondingly to and spaced above the scrap slide, means for driving said belt at high speed, and a hopper mounted upon the frame and having a discharge opening for feeding material to the conveyor belt at the bottom of the top flight of said conveyor belt, the upper end of said top flight of the conveyor belt being located in back of the screen so as to impel sand to be conditioned at high speed against said screen, scrap material being deflected by the screen to the upper end of said inclined scrap slide, said screen terminating at its lower end above the path of material gravitating to said slide, whereby to limit passage through the screen to material impelled upwardly thereagainst.

4. Sand conditioning apparatus as in claim 3, and wherein said apparatus includes a hinged weighted baffle mounted upon the hopper adjacent the upper end of said top flight of the conveyor belt, in the path of sand to be conditioned.

JOHN HERMAN SEEING.
